ELECTRIC ARC WELDER

Lincoln W. Cross, York, Pa., assignor to General Electric Company, a corporation of New York

Application September 28, 1954, Serial No. 32,461

Term of patent 14 years

(Cl. D26—5)

Fig. 1

Fig. 2

Fig. 1 is a front perspective view of a welder embodying my new design, and Fig. 2 is a back elevational view thereof.

The side of the welder not shown in Fig. 1 of the drawing is the same in appearance as that shown therein.

I claim:

The ornamental design for an electric arc welder, as shown and described.
